UNITED STATES PATENT OFFICE.

THEODORE W. HANRATH, OF CHICAGO, ILLINOIS.

WOVEN SURGICAL BANDAGE.

SPECIFICATION forming part of Letters Patent No. 781,142, dated January 31, 1905.

Application filed March 19, 1904. Serial No. 198,929.

To all whom it may concern:

Be it known that I, THEODORE W. HANRATH, a citizen of the United States, residing in the city of Chicago, county of Cook, and State of Illinois, have invented a new and useful Improvement in Woven Surgical Bandages, of which the following is a specification.

My invention relates to bandages for the use of surgeons and others; and the objects of the invention are, first, to provide a bandage which shall be flexible and yielding, and, second, to provide a bandage which shall not fray or ravel on the edges. I attain these objects by a bandage constructed as illustrated in the accompanying drawing, in which the single figure represents a general view of a bandage constructed in accordance with my invention.

My bandage is of any desired width, and consists of a strip of fabric, preferably linen or cotton, wherein the warp-threads *a* run obliquely across the strip and the filling or woof threads *b* also run obliquely across the strip, approximately at right angles to the first. In consequence of this construction all of the threads terminate at the side of the bandage, and there are no threads which run parallel with the edge.

It is impracticable to form selvage edges on bandages, because it would make the edges too thick, the bandage too stiff and unyielding, and such selvage or hemmed edges would irritate the parts to which the bandage might be applied. On the other hand, in the ordinary cut bandages some of the threads run lengthwise and the threads at the edge are very apt to fray out, so that the edges of the bandage are not infrequently a mass of tangled threads, which must be pulled off or cut to enable ready manipulation of the bandage and prevent the embedding of these loose threads (either warp or weft) in the afflicted parts and causing irritation. Both of these objections are obviated in the present construction, wherein all of the threads run obliquely crosswise. The bandage is smooth and even throughout, so that there are no irritating hems or selvages, and since only the ends of the threads are exposed at the edges of the bandage no loose warp-threads or frayed weft ends are present to entangle the bandage or become embedded in a suppurated wound.

Another important advantage in this new bandage lies in its great flexibility and ability to yield or bulge at any point transversely or longitudinally, so as to readily conform to the shape of the part of the body to which it is applied and also be elastic without looseness, so as to permit considerable freedom of articulation of the joints when applied to a joint. For example, if there is a protuberance on the body it is only necessary for the threads of the bandage to spread slightly or to "work" one upon the other, so as to slightly change their relative positions, and that part of the bandage over the protuberance will conform closely to it, lying smoothly over the part without drawing or distorting the rest of the bandage and without producing uneven pressures due to such bulging. This characteristic is absent in a fabric where non-elastic threads run lengthwise of the bandage.

From the foregoing it will be seen that a bandage is provided which is elastic without the necessity of forming it of elastic material, which is conformable to protuberances without preliminary shaping, and which is absolutely non-frayable, without the necessity of providing it with selvage, hemmed, or otherwise-treated edges. Furthermore, a bandage constructed in accordance with my invention will stretch longitudinally and the obliquely-arranged threads will draw closely together, so that a bandage admitting of very tight wrapping, without, however, losing its transversely elastic and conformable properties, is secured.

What I claim as new, and desire to secure by Letters Patent, is—

An elastic, conformable, non-frayable surgical bandage; consisting of a strip of woven fabric composed of non-elastic warp and weft threads disposed at approximately right angles to one another, and extending obliquely with respect to the length of the strip from edge to edge thereof.

THEODORE W. HANRATH.
